(57) **CLAIM**

The ornamental design for a table top memorial fountain monument containing a transparent material with laser-induced images and an inscription, set up on a light stand, as shown.

DESCRIPTION

FIG. 1 is a front elevational view of a table top memorial fountain monument containing a transparent material with laser-induced images and an inscription, set up on a light stand, showing our new design;

FIG. 2 is a left elevational view thereof; and,

FIG. 3 is a top plan view thereof.
